240,751

PUTTER HEAD AND MOUNTING

David L. Taylor, 380 W. Carmel Valley Road,
Carmel Valley, Calif. 93924

Filed May 14, 1975, Ser. No. 577,398

Term of patent 14 years

Int. Cl. D21—02

U.S. Cl. D34—5 GH

FIG. 1.

FIG. 2.

FIG. 3.

FIG. 4.

FIG. 5.

FIG. 6.

FIG.
7.

FIG. 1 is a perspective view of the putter head and mounting showing my new design;

FIG. 2 is a top plan view;

FIG. 3 is an elevational view of the front striking surface;

FIG. 4 is an elevational view taken from the right end of FIG. 3;

FIG. 5 is a rear elevational view;

FIG. 6 is an elevational view taken from the left end of FIG. 3; and

FIG. 7 is a bottom plan view.

I claim:

The ornamental design for a putter head and mounting, as shown and described.
